FIG. 7.

Des. 972

Jacob Steffe, James Morton & John Currie of Philadelphia Pa.
Assignees to

M. W. Jackson and W. G. Woodin of Berwick Pa.
Letters Patent No. 972 Dated Oct. 22nd 1837.

The Schedule referred to in these Letters Patent and making part of the same.

To all whom it may concern:

Be it known that we Jacob Steffe James Morton
and John Currie all of the city of Philadelphia and State of Pennsylvania
have invented or produced a new and original design for a cooking stove, and
we do hereby declare the following to be a full and exact description of
the same. — On reference to the drawing.

Fig. 1 is a side view of our design for cooking stove.

Fig. 2, an end view looking in the direction of the arrow.

Fig. 3, a ground plan of the bottom plate.

Fig. 4 a ground plan of the upper plate of the stove.

Fig. 5 views of the legs.

Fig. 6. full sized section of the moulding round the upper plate.

Fig. 7. full sized section of the moulding round the lower plate.

A is the fire pot of the stove furnished with a moulding B at
the bottom which rests on the lower plate C, the fire-pot, together with the four

fluted columns D supporting the flue chamber E. The latter consists of the bottom plate a, upper plate b, two side plates c, and a front plate d. The oven consists of the front plate F, back plate F', top plate G, bottom plate H, and end plates I, the latter being furnished with doors J, having ornamental designs. The whole is supported on the ornamental legs illustrated in Fig. 5.

We claim the combination and arrangement of figures and forms represented in the accompanying drawing forming together the ornamental design for the plates of a cooking stove.

In testimony whereof we have set our names to

Ex'd this Specification before two subscribing witnesses.

J. M. P. Wallaces: Charles O. Freeman. Henry Howson.	Jacob Steffe. James Horton. John Currie.
